EUGENE PETERSON, OF NEW YORK, N. Y., ASSIGNOR TO WESTERN ELECTRIC COMPANY, INCORPORATED, OF NEW YORK, N. Y., A CORPORATION OF NEW YORK.

SYSTEM OF SPACE-DISCHARGE DEVICES.

Application filed March 4, 1924. Serial No. 696,766.

This invention relates to systems of space discharge devices, and more particularly to arrangements including devices of this character that are used to effect modulation.

5 In systems employing three electrode space discharge tubes heretofore proposed for combining electric waves, it has been customary to make use of the distorting effect produced upon the current flowing in the space path of 10 the tube caused by the non-linear relation between the potential applied to a control electrode in this path and the space current.

The present invention, however, provides 15 an arrangement in which modulation is accomplished substantially only in the circuit connected to the control electrode of the tube.

The term modulation as used in this application means the variation of the shape of a wave.

20 One object of the invention is to combine electric waves substantially only in the input circuit of space discharge tubes.

Another object is to operate a space discharge device with its control electrode varied in potential alternately positive and negative with respect to the cathode terminal, whereby a plurality of waves may be combined in the current set up in an input circuit of said device.

25 A further object is to so arrange a space discharge device that positive potentials of only very small value are impressed upon the control electrode thereof to effect modulation in the circuit connected thereto.

30 A still further object is to impede the current in the input circuit of a space discharge tube so that modulation takes place therein.

An additional object is to match the input 35 impedance of a space discharge tube, whereby electric waves may be combined in an input circuit thereof.

An additional object is to reduce the amount 40 of unmodulated carrier current transmitted from a space discharge tube system arranged 5 to produce grid current modulation.

A feature of this invention relates to a space discharge modulator wherein modulation is produced in the input circuit thereof.

45 A further feature relates to a space discharge modulator having an impedance comprising a space path of a second space discharge tube connected in its input circuit to limit the current from said tube.

A still further feature of the invention is

a push-pull organization of space discharge 55 tubes, which are arranged to combine waves in the input circuit thereof, for suppressing the unmodulated component of carrier current.

An additional feature concerns means to 60 reduce the amount of unmodulated component of carrier current transmitted from a modulator comprising a conjugate arrangement of circuits for impressing carrier components upon the modulator input and output 65 circuits in out of phase relation without producing parasitic oscillations or singing.

This invention makes use of the fact that the impedance, to the flow of current in the circuit connected between the cathode and 70 the control electrode of a space discharge tube, is, in general, large when the potential of the control electrode is negative and is relatively small when the potential is positive, to thereby effect the combination of 75 waves in this circuit. By maintaining the average potential of the control electrode at the same potential as the cathode terminal and by supplying a plurality of alternating electric waves or wave components to the 80 input circuit connected between this control electrode and the cathode of the tube, the control-electrode to cathode internal impedance of the tube will be large during the negative half waves and small during the positive 85 half waves, whereby the effects of said waves are combined.

In the present invention, an impedance element is placed in the tube input circuit, whereby for positive half cycles of the impressed 90 waves, a small positive potential is impressed on this electrode and for negative half cycles of the impressed waves the full negative potential is impressed thereon. This result is brought about by adjusting the impedance to a value such that when the current flows through it during positive half cycles of impressed waves substantially the whole drop of potential occurs across the impedance, but during negative half cycles, since no current 95 is flowing, the full input potential is applied between the control electrode and cathode.

Since the impedance of the input circuit, connected between the cathode and the control electrode of the space discharge tube, may 105 be caused to undergo wide variation under the action of the impressed waves, it is apparent that if a plurality of waves of different

frequencies are impressed upon this input circuit, they will be combined therein to form a modulated wave.

In a common form of space discharge tube, 5 the control electrode takes the form of a grid and for this reason the apparatus described above constitutes a grid current modulator.

It is to be understood that this system, 10 which will be described hereinafter in more detail, may be used to combine waves having different characteristics to produce a complex wave having characteristics corresponding to those of each of the original waves or it may be used to derive a desired component from a 15 complex wave.

Grid current modulators have an inherent stability of output with respect to amplitude fluctuations of the applied carrier wave. The 20 operation of such modulator has been found to be stable, even though the amplitude of the carrier wave is in excess of about 1½ times the amplitude of the modulating wave.

This invention may be embodied, and is described in connection with certain figures of 25 the drawings, in arrangements for reducing the amount of unmodulated carrier current transmitted from a grid current modulator. In one such arrangement, the carrier current is fed through a balanced transformer or hybrid coil from which two sets of taps are taken off, one to the anode circuit of the modulator and the other to the input or grid circuit. The hybrid coil has associated with it a balancing network arranged to balance the impedance of the oscillator. The two branch 30 circuits are thus rendered conjugate to prevent the production of parasitic oscillations caused by energy fed back from the output circuit to the input circuit.

40 In the drawings, various arrangements embodying the invention are illustrated.

Fig. 1 shows a space discharge device having a resistance in its input circuit for producing grid current modulation.

45 Fig. 2 illustrates a circuit similar to Fig. 1 in which the resistance is replaced by a space discharge tube.

Fig. 3 shows curves for explaining the operation of the invention.

50 Fig. 4 shows a grid current modulator in which a winding of a transformer connected in the input circuit has its impedance adjusted to balance the input impedance of the tube.

Fig. 5 shows the invention applied to a 55 discharge device for combining carrier and signal waves.

Fig. 6 illustrates an arrangement similar to Fig. 5 which includes discharge devices connected in balanced relation.

60 Fig. 7 illustrates an arrangement in accordance with this invention for reducing the unmodulated component of carrier current.

Fig. 8 illustrates an arrangement similar to that of Fig. 7 in which no losses to the modu-

lated output are interposed by the balanced 65 transformer.

Fig. 9 illustrates an arrangement similar to Figs. 7 and 8 in which a space discharge tube replaces the balanced transformer.

In the various figures of the drawings, 70 like reference characters have been used to indicate like parts.

Referring to Fig. 1, a space discharge tube 10 comprises an anode 11, a cathode 12, and a control electrode 13. An input circuit connected between the electrodes 12 and 13 of the tube comprises an impedance represented by a resistance 14 in series with the secondary winding of the transformer 15. An output circuit is connected to the cathode 12 and anode 11 and includes a space current source 16 herein shown as a battery and also the primary winding of transformer 17.

If alternating currents having different characteristics are supplied to the primary winding of transformer 15, variations of potential corresponding to the variations of current will be impressed upon the control electrode 13 of tube 10. The normal potential of this electrode is zero with respect to the cathode terminal.

When alternating currents are thus supplied to transformer 15, the potential of the electrode 13 is caused to vary from positive to negative values, these terms being used, of course, with reference to the cathode terminal potential which is taken as zero potential. Where the cathode itself has a difference of potential between its terminals, the zero reference is taken as the potential of that cathode terminal to which the grid circuit is connected. The input or grid circuit may be connected to either cathode terminal, but where the cathode potential difference is large or appreciable relative to the amplitude of the impressed waves it is obvious that a greater grid rectifying action is obtained by connecting the grid circuit to the positive than to the negative cathode terminal. It is well known that, when the control electrode 13 of tube 10 is negative, the input impedance of the tube, that is the impedance connected between the electrodes 12 and 13, is high. Hence, for negative potentials, substantially no current flows in the tube input circuit and consequently the full potential of the impressed waves is available at the cathode and control electrode. On the other hand, when the control electrode becomes positive, the impedance of the tube to impressed currents is relatively small. Consequently, current will

flow in the input circuit of the tube which current produces a drop of potential in the resistance 14. Thus the positive potential available between the cathode and control electrode of the tube is small. As the positive potential of impressed waves increases, the drop of potential in resistance 14 increases accordingly, whereby the positive potential

on the control electrode is maintained at a substantially constant low value. This potential on this control electrode regulates the space current in the tube as is well understood. By properly adjusting the value of this resistance, effective modulation of currents flowing in the grid-cathode circuit is produced and the modulated grid waves are repeated into the anode-cathode circuit in accordance with the well-known principles of operation of the three-electrode tube.

This current limiting effect is illustrated by the curves shown in Fig. 3 in which abscissæ represent grid potentials and ordinates represent values of plate current. The full line curve represents the normal grid potential plate current characteristic of a tube, such as tube 10, with impedance 14 omitted. The dotted portion of the curve represents the effect of the impedance 14 in limiting the flow of plate current. It will be noticed that for changing positive potential of the control electrode 13, the rate of change of plate current is very small as compared to its rate of change for changing negative potential, impressed upon this electrode.

Thus, it is apparent that when the control electrode is positive, the effect of the resistance 14 is to limit the plate current in the tube. When components of side band and unmodulated carrier frequency are supplied to the input circuit, they will be combined in this circuit to impress a potential varying in accordance with the modulating wave upon the control electrode of the tube, whereby detection or demodulation is effected in the input circuit.

Referring to Fig. 2, the space discharge tube 10 has connected in its input circuit a second space discharge tube 18 comprising a cathode 19 and an anode 20. The cathode of tube 18 is connected to the cathode of tube 10 and the anode of tube 18 is connected in series with the secondary winding of transformer 15 to the control electrode 13 of tube 10. The leak resistance 20^a is connected in shunt to the input circuit of tube 10. The output circuit of this tube which is connected between its plate and cathode includes a resistance 21 short-circuited by switch 22 in series with primary winding of transformer 17 and battery 16.

The action of the modulating circuit of Fig. 2 may be explained as follows: suppose the potential of the grid 13 of tube 10 is made positive with respect to the anode 20 of tube 18. The grid 13 of tube 10 will then be positive relative to its filament 12 and current will tend to flow through the circuit. The resistance of the filament-grid path in the tube will drop correspondingly. On the other hand the resistance of the filament anode path of tube 18 remains high since the filament is positive with respect to the anode. The potential will then divide according to the respective resistance of tube 10 and the shunt circuit comprising

in₁ leak resistance 20^a on one hand and tube 18 on the other. The net result is that almost the entire impressed voltage is in effect applied across that tube whose grid is made negative. The leak resistance 20^a is inserted to prevent accumulation of a negative charge on the grid of tube 10 and anode 20 of tube 18.

The limitation of space current may be regulated by changing the battery 16 or by including the resistance 21 in the plate circuit by opening switch 22. It is apparent, by reference to the curves of Fig. 3, that if the cut-off is caused to occur above the knee of the full line curve, for negative voltages on the control electrodes, the relation between control electrode voltage and anode current will be non-linear. In this instance modulation will occur in the anode circuit in a manner well understood. With the cut-off occurring as indicated by the full line in Fig. 3 it is apparent that during the negative portions of the input waves the plate currents set up by these waves will bear a substantially linear relation to the input waves when the amplitudes are small enough to be confined to the linear part of the characteristic curve, but will bear a non-linear relation to the input waves for greater amplitudes.

This means that for small input amplitudes there will be no modulation produced in the anode circuit, but the modulation will be confined to the grid circuit. Even where the amplitudes of the input waves would be sufficient to sweep over the curved portion of a given tube characteristic such as that of Fig. 3, modulation could be reduced or prevented by including a resistance such as resistance 21 in the plate circuit, this resistance being large enough to have the effect of straightening out the tube characteristic or in effect changing to a new characteristic. Thus, it is seen that by designing resistance 21, of proper value the characteristics may be shifted to a position with respect to the zero ordinate such that grid current modulation and anode current modulation may be caused to take place simultaneously.

It is also possible by employing a reactive impedance element or a phase shifting network at an appropriate point in the system, for example, in place of resistance 21, to control the relative phases of the grid current and anode current modulation products, so that these products may be supplied additively to a common load circuit.

The effect of tube 18 in limiting the current in the anode circuit of tube 10 is illustrated by the straight line portion of the curve of Fig. 3 on the right-hand side of the zero axis. This indicates that the cut-off of plate current in this instance is much more abrupt than when the resistance 14, as shown in Fig. 1, is used.

In Fig. 4 a modulator 30 is connected in tandem to an amplifier 35. The amplifier 35 comprises the three-electrode space discharge tube 36 having an input circuit including the

secondary winding of the transformer 37 and a resistance 38 in series connected between its cathode and control electrode. The output circuit including the primary of the transformer 39 in series with a battery 40, extends from the cathode to the anode of tube 36.

Modulator 30 comprises a three-electrode space discharge tube 41 having an input circuit connected between its cathode and control electrode, and an output circuit connected between its cathode and anode. The input circuit includes the secondary winding of transformer 39, the impedance of which is such as to match the tube input impedance for alternating current when the control electrode is negative. The output circuit includes the primary winding of an output transformer 42. The secondary winding of transformer 42 has its terminals connected to a band pass filter 43 designed to have a very low shunt impedance to currents of frequencies outside of the transmitted band and a high shunt impedance to currents within the frequency band to be transmitted. The impedance of this filter within the transmitted band may be such as to match the tube output impedance.

In the operation of the circuit shown in Fig. 4, waves of signal frequencies are transferred by the transformer 37 to the input circuit of the amplifier 35. These waves are amplified by amplifier 35 in a manner now well understood and impressed on the input circuit of tube 41. Modulation is effected by the variable input impedance of the tube, which results when the control electrode goes positive and negative during different parts of the cycles of the impressed waves. When the grid is driven positive the input impedance of the tube drops to a comparatively low value, while, during the time that the grid is driven negative, the input impedance is very high and is almost entirely capacitive, being, therefore, dependent upon frequency. The input impedance of the tube is dependent upon the impedance of the load connected to the output circuit.

By inserting an impedance of appropriate value as described in connection with the preceding figures in the control electrode circuit the greater part of the potential drop can be made to take place across this external impedance when the control electrode is driven positive while during the negative part of the cycle the potential may divide equally across the tube and the external impedance.

Although the external impedance may take the form of a resistance or an inductance, it has been found convenient to have the impedance of the secondary winding of transformer 39 serve as the external impedance, thus avoiding the introduction of additional losses in the control electrode circuit. The ratio of transformer 39 is preferably made such that

the impedance of the secondary winding will match the input impedance of tube 41 for alternating currents when the control electrode is driven negative. The potential of the control electrode is normally zero.

In this case, the positive peaks of the input wave are more or less completely suppressed between control electrode and filament while the negative peaks are transmitted without variation and modulation takes place in the control electrode circuit. A modulated voltage is therefore effective on the control electrode of the tube 41. This voltage is then amplified in the anode circuit and the same impedance relations should obtain in this circuit as in the ordinary power amplifier, that is, the external impedance should be made equal to the internal output impedance of the tube. This is accomplished by proper design of filter 43 which is of the general type disclosed in Patent No. 1,227,113 to Campbell, issued May 22, 1917.

The load impedance in the anode circuit has a material effect upon the input impedance of the tube when the control electrode is negative. When the load impedance is zero the input impedance of the tube is at its greatest value and when the load impedance is infinite the input impedance of the tube is least. Thus, the impedance of the load circuit connected to the anode circuit of the tube 41 determines the transformation ratio of the transformer 39 to be used in its input circuit.

The arrangement of the amplifier 35 between the modulator 30 and the input circuit connected to the transformer 37 produces a stabilizing effect upon the impedance of the modulator circuit as a whole with respect to the line to which its input may be connected. The impedance of the secondary winding of the transformer 39 should preferably match the input impedance of tube 41 when the load circuit of the tube comprises the band pass filter 43. This filter is designed to have low shunt impedance for currents of frequencies outside the transmitted band, particularly to the band of signal frequencies and to the carrier frequency but to have high shunt impedance for currents within the frequency band to be transmitted. Thus, the input impedance of the tube 41 has a high value at carrier and signal frequencies and the corresponding voltages applied to the control electrode of this tube are therefore large, when the input transformer is given the high ratio required to match the input tube impedance as described above.

On the other hand, it may be more desirable to obtain the maximum advantage from the anode circuit as an amplifying device selective to the modulated wave. It is obvious, that, to do this, provision must be made for reducing to a negligible amount the flow of all currents in the anode circuit ex-

cept those within the frequency band to be transmitted. For example, filter 43 may be designed to have a very high shunt impedance for all frequencies outside the frequency band 5 to be transmitted and to match the internal output impedance of tube 41 for frequencies within the transmitted band. The entire power which tube 41 draws from battery 40 is by this means delivered to the frequency 10 band to be transmitted.

In the system shown in Fig. 5 modulated carrier waves are produced by combining waves from signal source 51 with carrier waves from source 52. The sources of waves 15 51 and 52 are connected to a common circuit coupled to the input circuit of a modulator 50 by a transformer 54. The signal source 51 is connected to the common circuit through a transformer 53. The common circuit also 20 comprises a low pass filter LPF which has its input terminals connected to the secondary winding of transformer 53 and a high pass filter HPF which has its input terminals connected to the carrier current source 52. 25 Filters LPF and HPF may be of the general type disclosed in Patent 1,227,113 to George A. Campbell, issued May 22, 1917. The output circuits of filters LPF and HPF are connected in series with the primary 30 winding of transformer 54. Filter LPF is arranged to freely pass without substantial attenuation, all currents having frequencies within the range of signals supplied by source 51, and to attenuate currents of frequencies above this range and especially current of the frequency produced by source 52. High pass filter HPF is arranged to pass currents having frequencies within a given band in which is included the frequency 35 of source 52 and to attenuate currents of frequencies below this band and especially currents of the frequencies produced by signal source 51. The secondary winding of transformer 54 is connected in the input circuit 40 of a space discharge tube 55, which circuit is connected to a control electrode and cathode of the tube. The input circuit includes a filter F which may be of the general type described by G. A. Campbell in 45 Patent 1,227,113, issued May 22, 1917. Tube 55 has an output circuit connected to its cathode and anode which includes the primary winding of an output transformer 56 in series with a space current battery 57. 55 The secondary winding of transformer 56 may be connected to a power amplifier supplying a signal modulated wave to an antenna, or it may be connected to a transmission circuit such as a wire line. 60 Modulator 50 is arranged to operate in accordance with the principles already set forth wherein modulation is effected in the circuit connected to the control electrode of tube 55. The secondary winding of transformer 54 which is included in this circuit

may perform a function similar to the secondary winding of transformer 39 in Fig. 4. However, it has been found for certain frequencies of the carrier and signal currents, that the impedance of the transformer winding is a function of frequency. To make the voltage of the waves impressed by sources 51 and 52 upon the control electrode during the negative peaks as large as possible, the tube impedance should be matched by the transformer and to cut off the positive peaks most effectively the impedance of the external circuit to these waves should be as large as possible. It is also necessary that the external impedance of the control electrode circuit between the cathode and grid should be very large for the frequency components produced by modulation, that is, the side band frequency. The variable impedance of the transformer winding to low frequencies may 70 result in poorer transmission of the side band at 100 cycles, for example, than at 2,000 cycles and will tend to produce distortion of the signals. In order to make uniform the impedance of the control electrode circuit to the side band frequencies, the filter F is provided which is designed to have the requisite impedance to the side band frequencies, but to pass the signal frequency waves and the carrier frequency waves from sources 51 and 52. 75 In order that the voltage impressed upon the control electrode of tube 55 by waves from sources 51 and 52 may be as large as possible, the impedance of the filter F to these waves is made large to match the tube impedance. 80 85 90 95 100

In Fig. 6 is shown a push-pull arrangement of grid circuit modulators in which three-electrode space discharge tubes 61 and 62 have their input circuits respectively extending from their cathodes to their control electrodes symmetrically connected with reference to carrier and signal sources, a lead 63 common to both input circuits includes the secondary winding of transformer 64, the primary winding of which may be connected to a source of carrier waves. One terminal of the lead 63 is connected to a point intermediate to the cathodes of tubes 61 and 62 and the opposite terminal of this lead is connected to the midpoint of a secondary winding of transformer 65, the outer terminals of which are respectively connected to the control electrodes of tubes 61 and 62 in series with resistances 66 and 67. The primary winding of transformer 65 is connected to a source of signal currents. Tubes 61 and 62 have balanced output circuits connected to the cathodes and anodes respectively thereof and including the primary winding of a transformer 68. The balanced output circuits comprise a common lead extending from the cathodes to the midpoint of the primary winding of the transformer 68, a battery 69 being included therein. The secondary winding of transformer 68 is provided with terminals arranged to be 110 115 120 125 130

connected to a transmission line or receiving device.

The operation of the circuit of Fig. 6 is, so far as the differential connection of the tube 5 output circuits is concerned, similar to that described in Patent 1,343,307, issued to J. R. Carson, June 15, 1920. As in the case of the Carson modulator referred to, one purpose of this push-pull arrangement is to suppress 10 in the output circuits of tubes 61 and 62 the unmodulated component of carrier frequencies. However, the modulating action of the circuit of Fig. 6 differs from that of the Carson patent in that in the present circuit the 15 modulation products are produced in the grid circuits of the tubes 61 and 62 and are reproduced in the anode-cathode circuits by the controlling effect of the grid potentials on the anode currents. In the Carson patent, on 20 the other hand, the input waves are repeated into the anode-cathode circuits and the modulation products first appear in the anode-cathode circuits as a result of the non-linear relation between grid potential and anode 25 current. The resistances 66 and 67 function in the same manner as resistance 17 of Fig. 1.

In Fig. 7 a modulator M, which may be similar to the one described in connection with Fig. 5, is arranged to be supplied with 30 signal frequency waves by the transformer 71 and with carrier frequency waves from a source 72 through a differential potentiometer 73. The output circuit of modulator M is coupled by transformer 74 to one winding 35 of a balanced transformer or hybrid coil 75. The output terminals of transformer 75 are connected to the input terminal of a filter 76 also having its output terminals connected, for example, to a wire line or a receiving 40 system, a power amplifier, etc. A balancing impedance or artificial line 77 is connected to the opposite terminals of transformer 75 and is designed to have impedance characteristics similar to the combined 45 impedance of the filter 76 and wire line or other apparatus connected to the filter. The midpoints of windings 78 and 79 of transformer 75 are connected to one half of differential potentiometer 73, whereby an unmodulated 50 wave of the carrier frequency may be impressed upon these windings. Connection is preferably so made that the component of carrier frequency impressed directly from the source 72 upon the hybrid coil 75 is in 55 out of phase relation with the component impressed by way of modulator M whereby the latter component is substantially reduced in amplitude.

In Fig. 8 is shown a slightly different circuit 60 arranged to function similar to the circuit of Fig. 7. In the circuit here shown the source of carrier waves 72 is connected directly to the windings 78 and 79 of hybrid coil 75 and an artificial network N is pro-

vided to balance the impedance of source 72 65 for current of the carrier frequency.

A wave of carrier frequency from source 72 is impressed upon the input circuit of a space discharge modulator 80 which may be arranged to operate in accordance with the 70 method described in connection with Fig. 5. Transformer 81 is arranged to impress signal frequency waves upon the input circuit of tube 80. By means of a transformer 82, which is connected through an adjustable resistance network 83 to the midpoints of windings 78 and 79, an unmodulated component of the carrier frequency of suitable amplitude is impressed upon the output circuit of tube 80. The circuit including the 75 network 83 and transformer 82 is so arranged that waves of the carrier frequency impressed on the output circuit are in out of phase relation with waves produced therein by the action of modulator 80, whereby the 80 amplitude of waves of the carrier frequency in this circuit is substantially reduced. A transformer 84 is provided to transmit signal modulated currents from the output circuit.

In Fig. 9 an auxiliary tube 85 is arranged 90 to perform a function similar to that of the balanced transformer or hybrid coil 75 in Figs. 7 and 8. Tubes 80 and 85 are connected to a source of carrier waves 72 so that the carrier current through auxiliary tube 85 opposes to a greater or lesser degree, the carrier current output from the demodulator 80 without affecting the side band output. By movement of the adjustable contacts on resistance 86 differentially connected to the input circuits of tubes 80 and 85, any degree of opposition may be secured. Modulating current is supplied to the input circuits of tubes 80 and 85 by means of transformer 860.

The arrangements shown in Figs. 8 and 9 105 are applicable to modulators operating in accordance with the principles set forth herein, that is utilizing grid effects, but are not applicable to the type of modulation heretofore proposed utilizing space discharge 110 tubes since in such modulators a component of carrier frequency is required in the anode circuit to produce modulated waves, that is side band frequencies.

Although this invention has been described 115 in connection with certain specific embodiments, it is apparent that the principles herein disclosed are susceptible of numerous other applications without departing from its scope. It is intended, therefore, that this invention is to be limited only by the scope of the appended claims.

What is claimed is:

1. In a modulator, a space discharge tube 125 having a cathode, an anode, and a control electrode, an input circuit connected to said cathode and control electrode, means for impressing waves of a plurality of frequencies

- upon a circuit connected between said cathode and control electrode, and means including a space discharge path from said cathode to said control electrode to cause said waves to 5 produce in said circuit current components representing the combination products of said impressed waves.
2. In a modulating system, a three-electrode space discharge tube, an input circuit connected to two electrodes of said tube, an output circuit connected to one of said two electrodes and a third electrode of said tube, means for supplying waves to said input circuit, at least one of said waves being of complex form, and means including a space discharge path between the electrodes connected to said input circuit for producing under control of said waves currents in said input circuit representing the combination products 15 between said supplied waves.
3. A modulator which comprises a space discharge tube having a cathode, an anode, and a grid electrode, an output circuit between said anode and cathode, sources of 20 high frequency waves and low frequency waves connected to said grid and cathode, and means in circuit with said sources and said grid and cathode for producing current flow in said grid-cathode circuit such that the 25 potential between said grid and cathode corresponds to said high frequency wave varying in amplitude in accordance with said low frequency wave, whereby correspondingly varying waves are repeated in said output circuit, said means including a space discharge path between said grid and cathode.
4. An electric system comprising a three-electrode space discharge device, input and output circuits therefor, means for supplying 30 waves having different characteristics to said input circuit, and means included in said input circuit for effecting modulation of one of said waves by another of said waves, said last means comprising an impedance in the 35 input circuit of such magnitude that most of the potential drop produced by current flow in the input circuit resulting from application of said waves occurs across said impedance.
5. In a modulator, a space discharge tube having an input circuit and an output circuit, each of said circuits including a space discharge path through said tube, and means for causing modulation to be produced within 40 said tube in both of said circuits.
6. The method of modulating alternating current of one frequency in accordance with alternating current of a different frequency by means of a space discharge device having 45 input and output circuits which comprises impressing currents and voltages of both frequencies upon an input circuit of large impedance, thereby controlling the amplitude of one of the half cycles of currents so that sub- 50 stantial modulation results in the input circuit, and the modulated component is repeated in amplified form in the output circuit.
7. The method of combining alternating currents having different characteristics by 55 means of a space discharge device having an input circuit associated therewith which comprises supplying said alternating currents of different characteristics to said input circuit, and impeding the respective half cycles 60 of the alternating currents differently in said input circuit.
8. The method of combining alternating currents having different characteristics by 65 means of a space discharge device having an input circuit associated therewith which comprises supplying said alternating currents of different characteristics to said input circuit, and substantially suppressing in said input circuit, one half of each cycle of the alternating 70 currents.
9. A wave combining circuit comprising a space discharge device having cathode, anode and grid or impedance-controlling elements, an input circuit associated with said grid and 75 cathode, means to impress on said input circuit waves of a plurality of components to be combined, said input circuit including sufficient impedance to cause the production in 80 said input circuit of current components representing the combination products of the impressed wave components, and a circuit associated with the anode and cathode for utilizing the combination products set up therein 85 from said input circuit.
10. A wave combining circuit comprising a space discharge device, having cathode, anode and control elements, means for applying to the cathode-control-element circuit of 90 said device waves of different components to be combined, means also included between said cathode and control elements situated to divide the potential of said different wave components between itself and the cathode-control element space of said device in a non-linear relation whereby combination components between the impressed waves are applied to said cathode and control elements, 95 and a utilization circuit for the combination components associated with said cathode and 100 anode.
11. A wave combining circuit comprising a space discharge device having cathode, anode and grid or impedance-controlling elements, an anode-cathode circuit, circuit means to impress across the grid and cathode a plurality of waves to be combined, said circuit means including series impedance whereby 105 said waves set up current-flow through said impedance and also vary the potential of 110 said grid alternately positive and negative with respect to the cathode, said impedance being of sufficient magnitude to make the po- 115

- tential variations on said grid non-linearly related to the impressed waves whereby combination components are repeated into the anode-cathode circuit.
- 5 12. A wave-combining circuit comprising a space discharge device having a cathode, an anode, a grid or impedance-control element, and means to supply space current between the anode and cathode, an output circuit connected to the anode and cathode, a circuit for impressing across the grid and cathode voltage components representing the waves to be combined, the connections from the grid to the cathode maintaining the grid at an average
- 10 potential such as to allow the impressed voltages to drive the grid potential positive and negative with respect to the cathode, said circuit connected across the grid and cathode containing sufficient impedance to cause the
- 15 production in the grid-cathode circuit of current-components representing the combination products of the impressed waves, whereby said products are repeated into said output circuit.
- 20 13. A wave combining circuit comprising a space discharge device having cathode, anode and grid or impedance-control elements, an input circuit associated with the grid and cathode, an output circuit associated with the
- 25 anode and cathode, means to set up in said input circuit current flow restricted to the half waves of one sign of a plurality of waves to be combined, and a dissipative impedance associated with said input circuit in the path
- 30 of flow of said half waves of current whereby the potential drop across said impedance accompanying such current flow is applied to said grid, and a utilization circuit for the combination components of said waves connected to said output circuit.
- 35 14. The method of employing a space discharge device of the type having a cathode, an anode and a grid or impedance-control element to combine waves of different characteristics, comprising utilizing the rectifying property of the grid-cathode internal impedance of the device to confine current flow in an external grid cathode circuit to half waves of one sign in the case of all of the
- 40 applied waves, developing in said external circuit a potential drop proportional to the said currents in such direction as to lower the average grid-cathode voltage producing such rectification, and utilizing the resultant grid-cathode potential to control the flow of space current in an external anode-cathode circuit associated with said device.
- 45 15. The method of operating a space dis-
- charge device of the type having cathode, anode and grid elements, to combine waves of different frequencies, which comprises the steps of applying the half waves of potential of one sign across the grid and cathode of said device and causing the half waves of opposite sign to produce current flow through a dissipative impedance associated with said device such that the accompanying drop of potential through said impedance is applied to the grid superposed on the half waves of potential, and utilizing the resulting grid-to-cathode potentials to control the flow of current in an external circuit associated with the anode and cathode.
- 50 16. A wave combining circuit comprising a pair of space discharge devices each having cathode, anode and grid or impedance-controlling elements, an input circuit having a portion common to the cathodes and portions individual to the grids of said devices, impedance means in the portions individual to the grids, and means for impressing on said input circuit a plurality of waves to be combined, such that said waves drive the potentials of said grids positive and negative with respect to the cathodes and produce in the individual portions of the input circuit current components representing the combination products of the impressed waves, such components being of respectively opposite phase in the two individual input circuit portions, and other components in the same phase in said individual circuit portions, and an outgoing circuit differentially associated with said anodes and cathodes whereby the combination products are repeated into said outgoing circuit while the other mentioned components of like phase are suppressed in said outgoing circuit.
- 55 17. A wave combining circuit comprising a pair of space discharge devices each having cathode, anode and grid or impedance controlling elements, a divided input circuit having a central branch common to said cathodes and outer branches individual to said grids, a source of waves differentially associated with said outer branches, a second source of waves associated with said central branch, impedances in said outer branches of sufficient magnitude to produce current components in said branches representing the combination products of waves from said two sources, and an outgoing circuit differentially associated with said anodes and cathodes.
- 60 In witness whereof, I hereunto subscribe my name this 29th day of February A. D. 1924.
- EUGENE PETERSON.
